UNITED STATES PATENT OFFICE.

CLAIR E. RYDER, OF SIOUX RAPIDS, IOWA.

PERFORATOR ATTACHMENT FOR PRESSES.

1,356,313.

Specification of Letters Patent. Patented Oct. 19, 1920.

Application filed May 22, 1919. Serial No. 298,943.

To all whom it may concern:

Be it known that I, CLAIR E. RYDER, a citizen of the United States of America, and resident of Sioux Rapids, Buena Vista county, Iowa, have invented a new and useful Perforator Attachment for Presses, of which the following is a specification.

The object of this invention is to provide improved means for perforating a sheet, on either horizontal or perpendicular lines, during the operation of printing said sheet, without subjecting the perforating element or elements to contact with inking rollers.

A further object of this invention is to provide improved means for gripping a sheet to a tympan conjunctively with perforating said sheet on selected lines during the operation of printing said sheet, and utilizing the gripping means for stripping the sheet from the perforator, without shifting the sheet laterally of the tympan or in any manner affecting its register or imprint.

A further object of this invention is to provide an improved means for connecting a lateral bar to a perpendicular bar.

A further object of this invention is to provide improved means for making intersecting lines of perforations in a sheet during the operation of printing said sheet.

My invention consists in the construction, arrangement and combination of elements hereinafter set forth, pointed out in my claims and illustrated by the accompanying drawing, in which—

Figure 1 is an elevation illustrating one form or assemblage of my improved devices. Fig. 2 is an elevation, partly in section, on an enlarged scale, of parts of the devices. Fig. 3, is a cross-section on the indicated line 3—3 of Fig. 1, on an enlarged scale, a part of the lateral bar being shown in section to reveal interior construction. Fig. 4 is a cross-section on the indicated line 4—4 of Fig. 1, on an enlarged scale.

In the construction of the device as shown the numeral 10 designates a gripper bar now common and well known in flat-bed platen presses and usually employed to carry two gripper arms arranged perpendicular to the bar adapted to hold a sheet of paper or other material to be printed against a tympan. In my improved construction one or both of the ordinary gripper arms are omitted and in place thereof combined gripper and perforator devices

are substituted, which devices are carried by the gripper bar and moved through an arc thereby. The devices are made and assembled of such thickness as not to restrict or limit the impression of the type on the sheet and yet serve to effect perforation of said sheet as desired and operate to strip the sheet from the type and from the perforating elements. In the drawing I have shown the omission of both the ordinary gripper arms and substitution therefor of two combined gripper and perforator devices; but it is to be understood that as to one of said devices the perforating element may be omitted or a modified common arm may be employed. Each of the combined gripper and perforator devices is constructed as follows: An arm 11 is secured at one end to the bar 10 preferably by a bolt 12 and extends perpendicular to said bar and is adapted to be moved through an arc by ordinary oscillation of said bar to and from a position in a printing form between or at one end of the type therein and over and in contact with furniture used in a common manner to assemble said form. A longitudinal groove 13 is formed in the arm 11 and opens therefrom toward the tympan, and a perforator plate 14, having perforating elements such as teeth 15 formed on one margin, is mounted in said groove and the toothed marginal portion of said plate projects from said groove toward said tympan. The plate 14 may be secured to the arm 11 in any desired manner; but preferably is removable and replaceable and the fastening means should be convenient of manipulation and effective in maintaining a rigid connection. For that purpose I have shown set screws 16 seated in the arm 11 and intersecting the groove 13 and adapted to engage and lock the plate 14 in the groove. Any other suitable fastening means may be employed, such as wedges or dovetailing elements.

The combined thickness of the underlying furniture, bar 11 and projecting toothed portion of the plate 14 is substantially equal to or slightly greater than the height of type used in the form, in order that, when an impression is made, the toothed margin of the plate may penetrate the sheet without damaging the platen or destroying the tympan and avoiding building up or shaying the underlying furniture. A stripper 17 is arranged parallel with the grooved

face of the arm 11 and is provided with a series of pins 18 (five of said pins being indicated) rigidly secured by one end each to said stripper preferably by sweating or brazing. The pins 18 extend loosely within holes 19 extending through the arm 11 at right angles to the set-screws 16 and fit snugly yet slidingly therein. One end of each hole 19 is enlarged to form a chamber 20 surrounding a pin 18 and expansive coil springs 21 are mounted in the chambers 20, surround the pins and exert a yielding influence to separate the stripper from the arm. In the case of most of the pins 18, in this instance four, the outer ends of the springs 21 bear directly on the inner surface of the stripper; but as to the central pin additional expansion is desired. Therefore, a leaf spring 22, of semi-elliptic type, is mounted at its center on the central pin 18, bears at its center on the inner surface of the stripper 17 and receives expansion and support from the central spring 21, extends between the stripper and arm 11 and bears at its ends on the adjacent face of said arm. The pins 18, spring 22, springs 21 and stripper 17 are arranged at one side of the plate 14 and said stripper is susceptible of compression toward the arm 11, at each impression of the sheet, sufficiently to carry the stripper wholly beyond a plane common to the outer ends of the teeth of the plate, thus permitting the teeth to penetrate said sheet. The arrangement of pins and springs relative to the arm 11 and stripper 17 is such that they prevent longitudinal or sidewise movement of the stripper under and during the impression movement and thus prevent lateral movement of the sheet or creeping that would affect the register of the impression. When the impression is relaxed the stripper is moved outwardly or separated from the arm 11 by the interposed springs 21, 22 and effects a stripping of the sheet from the teeth of the perforating plate.

The construction thus far described covers the use of the improvements in making one line or parallel lines of perforations, dependent on whether one or more of the devices is employed. However, it is desirable at times to make another or other lines of perforations at right angles to the primary perpendicular line or lines. To this end one or more additional or supplemental arms 11^a, 11^b are employed. Each of the arms 11^a, 11^b is equipped with a stripper, pins, springs, and a perforating plate identical, except as hereinafter noted, with the equipment of the primary arm 11 and is used and operated in substantially the same manner and coincident therewith and with the same result as to perforating and stripping and overlying interposed and spacing furniture. Each arm 11^a, 11^b, is formed with end portions 65 having dove-tail mortises 23 lying at right angles to the groove therein for the perforator plate and each end portion is formed with a slot 24 also at right angles to said groove and opening to a mortise at its outer 70 end. Shouldered set-screws 25, in this instance one for each end portion, are mounted loosely in the outermost arm of each fork, extend across the slots 24 and are seated in the opposite arm. It is the function of the 75 set-screws 25 to contract the slotted ends of the arms 11^a, 11^b. Each arm 11 is formed with dove-tail tenons 26 adapted to be received in the dove-tail mortises of the arms 11^a, 11^b and be gripped by the end portions 80 of the arms to locate and retain said arms in desired relative arrangement. The perforating plates in the arms 11^a, 11^b preferably are notched at their ends so that toothed portions thereof may extend across the 85 planes of the tenons 26 and into intimate relation with the plates 14 on the arms 11. Thus each transverse line of perforations is caused to approach closely to or intersect the perpendicular line or lines of perforations. 90

Sometimes the spacing of type-forms in a given chase is quite narrow, as in the printing of coupon bonds or mortgages or small checks or receipts and it is desirable to limit the width of the perforating devices and 95 supports therefor to the accommodation of said spaces.

When it is desired to limit the perforating to one perpendicular line, a common gripper may be substituted for one of the devices 11 and, at other times, the device as shown may be employed with one or more of the perforating plates 14 removed.

I do not desire to be understood as limited to any precise construction shown as the 105 same may be modified in various particulars.

I claim as my invention—

1. A perforator attachment for presses, comprising an arm formed with a groove, a separate perforator plate rigidly held in 110 and projecting outside of said groove, a stripper arranged parallel with said arm and also parallel with a transverse plane of the plate when extended said stripper being adapted for movement toward and away 115 from said arm and across the plane of the outer margin of said perforator plate, pins fixed to said stripper and slidingly engaging said arm and springs interposed between said stripper and arm.
2. A perforator attachment for presses, comprising an arm formed with a groove, a separate perforator plate rigidly held in and projecting outside of said groove, pins 120 loosely mounted in said arm adjacent said groove, coil springs on said pins, and a stripper fixed to said pins and overlying said springs, said pins serving to guide and pre-

vent lateral and longitudinal movement of said stripper.

3. A perforator attachment for presses, comprising an arm formed with a groove, a separate perforator plate held rigidly yet removably in and projecting outside of said groove, pins slidably mounted in said arm and projecting therefrom, said pins being arranged in a row parallel with and adjacent to said perforator plate, said arm being formed with chambers surrounding said pins, coil springs on said pins and extending within said chambers, a stripper mount-

ed rigidly on the outer ends of said pins and overlying said springs, a leaf spring being interposed between said stripper and one of said coil springs, said stripper being normally spaced from said arm a distance greater than the projection of said perforator plate, said stripper being normally held, yieldingly in its outermost position by said springs.

Signed at Sioux Rapids, in the county of Buena Vista and State of Iowa, this 10th day of May, 1919.

25

CLAIR E. RYDER.
